(57) **CLAIM**

We claim the ornamental design for a brosteotome, as shown and described.

DESCRIPTION

Cross-reference is made to U.S. Utility patent application Ser. No. 14/506,582 entitled "Brosteotome and Method of Use" by Adam Carver et al., which is filed concurrently with the present application and is expressly incorporated herein by reference.

FIG. 1 is a front perspective view of a design of a brosteotome;

FIG. 2 is a front elevation view of the brosteotome of FIG. 1; FIG. 3 is a rear elevation view opposite the front elevation view of FIG. 2;

FIG. 4 is a side elevation view of the brosteotome of FIG. 1, with the opposite side elevation view being the mirror image of FIG. 4;

FIG. 5 is a distal plan view of the brosteotome of FIG. 1; and, FIG. 6 is a proximal plan view of the brosteotome of FIG. 1. The features shown in broken lines depict environmental subject matter only and form no part of the claimed design.
